CLAIM

The ornamental design for an infant car seat canopy, as shown and described.

DESCRIPTION

FIG. 1 is a top plan view of an infant car seat canopy showing my new design;

FIG. 2 is a front perspective view thereof;

FIG. 3 is a left side elevational view, the right being a mirror image thereof; the broken lines are for environmental purposes only and form no part of the claimed design; and,

FIG. 4 is a rear elevational view thereof.

FIG. 1.

FIG. 2.

FIG. 3.

FIG. 4.
